UNITED STATES PATENT OFFICE

2,318,492

AIR MATTRESS

John H. Johnson, Toronto, Ontario, Canada

Application January 16, 1941, Serial No. 374,679

2 Claims.

(CL. 5—348)

This invention relates to air mattresses or cushions in which a pair of rubber sheets secured together around the edges are connected at intermediate points by an intervening elastic member which forms tufts on either side to prevent undue expansion or bulging and the principal objects of the present invention are to obviate the rupturing of the outside rubber sheets through undue stretching adjacent to the "tufted" spots.

A further object is to devise a structure which will be very flexible and therefore much softer under the applied weight of persons lying or sitting thereon.

A still further object is to effect economy in the quantity of rubber used in the structure.

The principal feature of the invention consists in securing the outer sheets by means of a plurality of intermediate strips of material connected alternately to the top and bottom sheets, said strips being of elastic material and the spot contacts of the intermediate strips adhere in areas extending transversely thereof.

A further important feature consists in the novel construction and arrangement of a pocket at one end of the mattress enclosing a separate removable cushion.

In the accompanying drawings Figure 1 is a perspective view of a mattress constructed in accordance with this invention, a portion thereof being broken away to disclose the removable pillow structure at one end.

Figure 2 is an exaggerated longitudinal sectional view of the mattress structure before being inflated illustrating the manner of assembly of the outer envelope and the intermediate means connecting the outer rubber sheets.

Figure 3 is an enlarged longitudinal sectional view of a portion of the mattress shown inflated.

Figure 4 is a plan view of a portion of the mattress constructed in accordance with this invention having parts of the several layers of the structure broken away.

Figure 5 is a longitudinal sectional view of the inflated mattress taken on the line 5—5 of Figure 4.

Figure 6 is a fragmentary perspective view of a portion of an inflated mattress constructed in accordance with this invention.

In the manufacture of inflatable rubber mattresses it has been known to place a central rubber sheet between the two outer rubber sheets of the mattress envelope and to place on either side of the central sheet of rubber a perforated

sheet of paper to permit the adhesion of separated spots of the central sheet with the inner surface of both the top and bottom sheets of the structure.

5 Mattresses constructed in the above manner have been found to have very undesirable faults particularly in respect to the unequal stretch of the outer envelope sheet around the adhesion spots which form the tufts. Further, the mattress is not as flexible as may be desired.

10 The present invention overcomes these various objectionable features.

According to the present invention rubber sheets 1 and 2 of the mattress envelope are connected by means of a plurality of narrow rubber strips 3 which extend longitudinally from end-to-end of the mattress and are connected to the inner sides of the sheets 1 and 2 alternately so that the full width of the strips 3 is secured by 15 vulcanization to the inner side of the outer sheets in substantially rectangular areas which are indicated by the tuft areas 4 and 5 respectively.

20 The longitudinal strips 3 are thus alternately connected to the top and bottom sheets of the mattress envelope and form zig-zag connecting members which, when the mattress is inflated, limits the thickness or depth of the mattress and as the connecting strips are preferably of rubber they are sufficiently elastic to allow of a desirable 25 amount of expansion and as the strips are arranged parallel to each other and the tuft areas of the successive strips are staggered in relation to each other a very stable and uniform mattress is produced which is however extremely flexible.

30 The outer sheets 1 and 2 are of course secured together around the edges in the form of the flange 6 and consequently the tendency for side displacement of the top and bottom sheets is obviated.

35 In constructing a mattress such as described the bottom sheet 2 is laid upon a flat surface and a sheet of paper 7 is laid thereover. This sheet is of course of lesser width and length than the rubber sheet so as to leave exposed edges to form the edge flanges 6, and rows of rectangular perforations 8 are formed in the sheet. These 40 perforations are preferably of oblong form and are of slightly greater length than the width of the rubber strips 3. These rubber strips are then laid over the paper sheet 7 so that oblong rectangular areas, equally spaced apart, of the rubber strips will contact with the areas of the sheet 2 exposed by the perforations in the paper sheet. 45 A second paper sheet 9 is then laid over the 50

rubber strips and this second sheet is formed with perforations similar to the perforations 8 in the sheet 1 but the perforations 10 are offset and are placed midway between the perforations 8 in the lower sheet and they are arranged in longitudinal alignment with the lower rows.

The top rubber sheet 1 is then laid over the second paper sheet and its under surface comes into contact with the exposed narrow rectangular areas outlined by the perforations 10 in the upper paper sheet. The upper paper sheet is of course smaller than the outer rubber sheets and the edge surfaces of the two sheets engage in adhesive contact.

The sheets are thus placed together, and, as is illustrated in Figure 2, are then placed under pressure and vulcanized so that the narrow rectangular areas exposed by the perforations in the two paper sheets permit the adhesion of the longitudinal strips alternately to the upper and lower rubber sheets. The outer edges of the sheets 1 and 2 are also vulcanized together to form the outer seam.

A suitable valve 11 is vulcanized in position at one of the corners of the mattress so that it can be readily inflated.

At one end of the mattress it is desirable to provide a pocket to form a pillow structure not restricted by the tufting structure previously described. This is accomplished by laying an unperforated sheet of paper between the upper and lower rubber sheets 1 and 2 and it is preferred to have this pocket structure open at the end so that the paper sheet is extended out past the rubber sheets. This pocket may be closed by means of one of the standard types of slide fasteners 12 or otherwise as may be desired and when thus provided with an opening and closing means a suitable pillow or cushion 13 separate therefrom may be inserted into the pocket 14. This pillow may be a pneumatic pillow if desired, or, it may be desirable to simply seal this pillow area around the outer edges and provide it with a valve so that it may be inflated separately from the main body, there being a vulcanized strip 15 arranged at the end of the mattress between it and the pillow portion.

It will be understood that, with the longitudinal strips of rubber attached alternately to the upper and lower sheets of the mattress by transverse contact areas the full width of the strip, the stretching effect caused by the inflation of the mattress and later by the application of an external weight thereto, will apply the stretching effect across the full width of the longitudinal strips and the rectangular areas will distribute the stress to the outside sheets uniformly for the full width of each strip.

It will also be understood that there will be a considerable saving effected in the cost of the structure in that the total area of the rubber strips will be much less than the total area of a full intermediate sheet of rubber which has heretofore been used.

Further, it will be understood that the lateral resiliency of the mattress will be much greater with the strip structure than where an intermediate rubber sheet is used and such lateral resiliency relieves to a very great extent the stretching effect at the points of union between the central supporting member and the outer sheets.

10 A structure such as described provides a very highly desirable article which is extremely comfortable in use and will have an exceptionally long life.

Mattresses such as herein described are preferably made with an outer facing of textile fabric bearing a fancy pattern and in the manufacture it is desirable that the fabric of the underside be protected against the detrimental effects of steam in the vulcanizing process and it is also desirable to seal the several layers of the structure against the ingress of steam and moisture. To accomplish the above it is found desirable to cut the upper rubber sheet 1 larger than the bottom sheet so that a margin projects all round and this overlying top sheet is sealed down against the plate on which the mattress is fabricated. The under rubber surface of the top sheet may be pressed in a secure seal against the plate on which it is vulcanized or it may, if found desirable, be sealed down with a suitable cement.

20 The sealing of the top sheet down to the plate prevents steam and moisture getting in between the several surfaces and a secure vulcanization of the various members is effected. After vulcanizing, the extra width of the edge flange is trimmed off in a suitable manner.

25 What I claim as my invention is:

1. An inflatable air mattress of the type formed of a pair of rubber sheets sealed together at the edges having the top and bottom sheets connected on the inner side of the mattress by a plurality of parallel spaced flexible rubber strips, each of which is connected alternately to the inner surface of the bottom sheet and the top sheet, characterized in that the areas of connection of the said strips to the inner surfaces of the top and bottom sheets are alternately arranged in the adjacent strips so that the sloping plane of the portion of the strip connecting the bottom and top sheets in alternate strips are arranged to intersect the plane of the sloping portion of the intermediate strip to effect a balancing of the endwise stress on each adjacent strip, the zones of connection between the said strips and the upper and lower sheets in each alternate strip being disposed in staggered relation to the zones of connection between the adjacent strip and the upper and lower sheets.

2. An air mattress as claimed in claim 1 in which the contacting areas of the internally zig-zagged strips with the top and bottom sheets of the mattress are of rectangular form and extend the full width of the strips.

JOHN H. JOHNSON.
